UNITED STATES PATENT OFFICE.

LEON E. BING, OF INDIANAPOLIS, INDIANA.

JEWELER'S APPLIANCE.

1,037,196.

Specification of Letters Patent. Patented Sept. 3, 1912.

Application filed September 1, 1911. Serial No. 647,213.

To all whom it may concern:

Be it known that I, LEON E. BING, a citizen of the United States, residing at Indianapolis, in the county of Marion and 5 State of Indiana, have invented certain new and useful Improvements in Jewelers' Appliances; and I do hereby declare the following to be a full, clear, and exact description of the invention, such as will enable 10 others skilled in the art to which it appertains to make and use the same.

This invention relates to jewelers' appliances and has particular reference to a device for holding rings to facilitate the 15 process of engraving, filing and polishing.

The principal object of the invention is to provide a holder which is adapted to be supported by an engraver's block of the ordinary construction and which will obviate 20 the necessity of the engraver holding the work in his hand when working upon the same.

Another object of the invention is to construct a holder in such a way so that the 25 same may be rotated at will without the necessity of unclamping it from the engraver's block. Broadly, this object is attained by rotatably mounting a large ring within a base, said base being adapted to 30 be detachably secured to the engraver's block.

Another object of the invention is to provide an efficient means for securing the work within the large ring and this is done by 35 adjustably mounting a plurality of regularly spaced arcuate ring clamps in said ring.

A still further object of the invention is to provide a device made of a few number of parts which may be easily detached and 40 replaced when they become old or worn.

The advantages of this device will be readily apparent when it is seen that the necessity of handling the work is entirely obviated, for in polishing and buffing the 45 inside of a ring it sometimes becomes too hot to handle when it is necessary to turn the same so that it can be more readily worked upon. It will also be apparent that this device will greatly facilitate engraving and filing work which may be secured therein.

In carrying out the objects of this invention generally stated above it will be understood, of course, that the essential features 55 thereof are susceptible to changes in detail and structural arrangements, preferred and

practical embodiments being shown in the accompanying drawings wherein:—

Figure 1 is a perspective view of the invention showing the same attached to an 60 engraver's block. Fig. 2 is a view in side elevation and partly in section showing the means for adjustably mounting the clamps in the ring. Fig. 3 is a transverse sectional view taken on the line 3—3 of Fig. 2, and, 65 Fig. 4 is a modified form of the means for rotatably mounting the ring in its base.

Referring to the drawings by numerals it will be seen that the improved device is adapted to be supported by an engraver's 70 block 5 having in the top thereof a transverse groove 6. The base 7 is adapted to be seated in the groove 6 and in the preferred form, this base is made in three parts, 75 namely: a bottom strip and two vertically arranged spaced apart side strips suitably secured together. The upper edge of the side strip is curved as indicated at 8 in order that the work holder proper may be freely rotated between said vertical sides. In the upper corners of each strip there is placed a guide screw 9, said screws projecting through the sides of the base and slightly past the inner walls thereof, the purpose of 80 which will presently be described.

A large ring 10 having an annular groove 11 on each side and adjacent the outer periphery thereof is rotatably mounted in the base 7. The guide screws 9 are adapted to engage in the grooves 11 thereby forming an 90 efficient means for holding the ring 10 within its base and also guiding the same. At regularly spaced intervals the ring is provided with transverse elongated openings 12 which are adapted to receive the thumb 95 nuts 13.

A plurality of arcuate ring clamps 14 are adapted to be adjustably mounted within the ring by means of threaded openings 15 which project from the rear surface of each clamp at right angles thereto and intermediate the ends thereof and engage the thumb nuts 13. The clamps 14 are provided at their ends with guide pins 16 which project from the rear surface of said clamps parallel to the threaded pins 15 and through transverse openings in the ring 10. These openings are for the purpose of preventing the clamps from moving laterally relatively to said ring. Each clamp is provided upon its outer bearing surface with a pad 17 which will prevent the work which is held 100 105 110 115

between said clamps from becoming scarred. The inner periphery of the ring 10 is provided between two of the ring clamps 14 with a cut out portion 18 so that a ring having a large stone can be readily held between the clamps as is clearly shown in Fig. 1.

In the modified form of the base 7 as is shown in Fig. 4, said base is made of two sections which form a channel between the 10 vertical walls thereof. One of said walls is provided on its inner surface with an annular flange 19 which is adapted to engage one of the annular grooves 11 on the ring 10. The other groove 11 is engaged by a screw 15 9 such as is used in the preferred form.

In use, or when it is desired to engrave, polish or file a ring, the base 7 is disposed in the groove in the engraver's block and the work is then inserted within the ring 10 20 and the clamps adjusted by means of the thumb nuts 13 so that said clamps will securely hold the work in place. When it is desired to move the ring in order to more readily work upon the same all that is necessary is to grasp the ring 10 and rotate the 25 same within its base.

It will thus be seen from the foregoing description that the invention provides a simple and very effective appliance for holding rings while being worked upon. It will be understood, of course, that this device may be made of any suitable material and may also be made in different sizes although it may be made in just one size which will 30 accommodate any size.

Having thus described the invention what is claimed is:

1. A device of the class described comprising a base having upwardly extending spaced walls, a ring interposed between said walls, means to hold said ring in adjusted position between said walls, and adjustable work clamping means carried by said ring.

2. A device of the class described comprising a base having upwardly extending spaced walls, a ring interposed between said walls, said ring having a groove around one side, means extending inwardly from one wall

and into said groove adapted to guide and support said ring, and means carried by 50 the other of said walls adapted to clamp said ring in adjusted position.

3. A device of the class described comprising a base having upwardly extending spaced walls, a ring interposed between said walls, said ring having a circular groove around one side, a plurality of pins extending inwardly from one wall into said groove for guiding and supporting said ring, means extending through the other of said walls 55 for clasping said ring in adjusted position between said walls, and adjustable work clamping means carried by said ring.

4. A device of the character described comprising a base, said base having spaced 60 vertical walls, the upper edges of said walls being curved, guiding and supporting means carried by said walls, a ring carried by said guiding and supporting means, and means carried by said ring for holding work.

5. A device of the character described comprising a base, a ring rotatably mounted in said base, said ring being provided with regularly spaced transverse elongated openings, a plurality of arcuate clamps within 70 said ring, guiding and supporting means carried by said clamps and engaging said ring, and means in said elongated openings for adjusting said clamps.

6. A device of the character described comprising a base, a ring rotatably mounted in said base, a plurality of work clamps adjustable within said ring, an adjusting pin projecting from the rear surface of each of said clamps and through said ring, guide 80 pins projecting from each end of said clamps parallel to said adjusting pin, and means engaging said adjusting pin for adjusting said clamps.

In testimony whereof I have signed my 90 name to this specification in the presence of two subscribing witnesses.

LEON E. BING.
